FISHING ROD AND REEL CASE

Duane N. Mowat, Detroit, Mich., assignor to Hurd
Lock & Manufacturing Company, Detroit,
Mich., a corporation of Michigan

Application December 6, 1946, Serial No. 135,325

Term of patent 7 years

(Cl. D31—4)

To all whom it may concern:

Be it known that I, Duane N. Mowat, a citizen of the United States, residing at Detroit, Wayne County, Michigan, have invented a new, original, and ornamental Design for a Fishing Rod and Reel Case, of which the following is a specification, reference being had to the accompanying drawings, forming a part thereof, wherein:

Fig. 1 is a perspective view of a fishing rod and reel case showing my new design;

Figs. 2 and 3 are side and top views, respectively, thereof;

Fig. 4 is an end view thereof, taken from the left, Fig. 2; and

Fig. 5 is an end view thereof, taken from the right, Fig. 2.

The characteristic feature of the design for the rod and reel case resides in the specific configuration of the enlarged portion thereof as shown.

I claim:

The ornamental design for a fishing rod and reel case, as shown and described.
